UNITED STATES PATENT OFFICE.

CLARENCE R. PARTINGTON, OF RICHMOND, VIRGINIA.

BLOW-OFF FOR STEAM-BOILERS.

SPECIFICATION forming part of Letters Patent No. 655,988, dated August 14, 1900.

Application filed April 25, 1900. Serial No. 14,330. (No model.)

To all whom it may concern:

Be it known that I, CLARENCE R. PARTINGTON, a citizen of the United States, and a resident of Richmond, county of Henrico, State 5 of Virginia, have invented certain new and useful Improvements in Blow-Offs for Steam-Boilers, of which the following is a specification, reference being had herein to the accompanying drawings, in which—

10 Figure 1 is a vertical longitudinal sectional view of a blow-off pipe provided with my invention, and Fig. 2 a plan view thereof, the furnace-wall in both views being omitted.

15 The object of the invention is to provide a simple device for preventing the clogging of the blow-off pipe by the lodging of mud therein; and it consists of certain novel features of construction hereinafter described and claimed.

20 Referring to the drawings by reference-letters, *a* designates a portion of the steam-boiler, and *b* the usual blow-off pipe connected to the boiler at its bottom and near one end and extending out through the wall

25 of the furnace (not shown herein) and provided at a point outside of the wall with the usual blow-off cock *c*. The main part of the blow-off pipe is horizontal, and its inner end is turned upward to enter the bottom of the 30 boiler, this vertical part being connected to the horizontal part by a suitable elbow connection; but it is obvious that the blow-off pipe may have as many bends or turns as in practice may be desirable. Extending the

35 entire length of the main part of the blow-off pipe and inclosed therein is a rod *d*, preferably hollow and provided at frequent intervals with radial pins *e*. This rod extends from a point close to the cock *c* into the elbow

40 connecting the inner end of the pipe to the vertical portion thereof, and at this latter end it is pivotally connected to the downwardly-turned end of a bell-crank *f*, pivotally supported in the elbow. The other end of this 45 bell-crank is pivotally connected to a short vertical rod *g*, which is also provided with radial pins *e* at short intervals, and has its upper end guided by a suitable star-plate or spider *h*, secured to the interior of the boiler 50 over the opening leading into the blow-off

pipe, the rod *g* being provided with collars *i* on opposite sides of said star-plate to limit the movement of the rod *g*.

Interposed in the pipe *b* at a point near the cock is an enlarged casing *j*, within which is 55 pivoted another bell-crank *k*, the depending arm of which is pivotally connected to rod *d* and the horizontal arm of which is connected by a pin-and-slot connection to the inner end of a stem *l*, which reciprocates 60 through a stuffing-box *m* and is pivotally connected at its upper end to a hand-lever *n*, this lever being pivotally connected at one end to an upright link *o*, whose lower end is pivotally connected to a lug or ear formed integral 65 with a short tube *p*, connecting the stuffing-box to the top of the casing *j*. This tube *p* is screwed into an opening in the top of the casing and is threaded exteriorly at its upper end for the reception of the gland of the packing-box. This tube is also enlarged internally 70 for the reception of a guiding-collar *q* on the stem *l*.

It will be observed that by reciprocating the stem *l* by means of its lever a reciprocating movement will be imparted through the bell-cranks to the rods *d* and *g* and that the pins carried by these rods will agitate and dislodge any mud or sediment that may have collected in the piping, so that the mud or 80 other sediment may pass freely through the blow-off cock when the same is open. As will be observed, the agitators may be operated previous to opening the cock or during the blowing-off process, as may be found expedient. It will be thus observed that it will be impossible with my improvement for the blow-off pipe to be clogged by the caking of mud therein, thus avoiding a serious objection to the blow-off pipes now in general use. 85 As is well known, with the blow-off pipes as now generally constructed the mud settles into the same and is baked hard therein by the action of the fire of the furnace, so that when the blow-off cock is opened the baked 90 mud plugs up the same. As is obvious, I entirely avoid this objection by providing a cleaner or agitator that extends throughout the entire length of piping from the opening into the boiler close to the blow-off cock. 95 100

Having thus fully described my invention, what I claim, and desire to secure by Letters Patent, is—

1. In a blow-off device for steam-boilers, 5 the combination of a boiler, a blow-off pipe connected thereto and provided with a blow-off cock at a distance from the boiler, a casing in the pipe between the cock and the boiler, an agitator inclosed in the pipe and 10 extending from the cock, through the casing and to the opening into the boiler, and means extending into said casing for moving the agitator.
2. In combination, a boiler, a blow-off pipe 15 provided with a cock at a distance from the boiler, a reciprocating agitator inclosed in the pipe and extending from the cock to the boiler, and devices for reciprocating said agitator.
3. The combination, a boiler, a blow-off pipe 20 consisting of a vertical part and a horizontal part, the latter part being provided with a cock, reciprocating agitator-rods extending through both parts of the pipe and

connected together, a casing interposed in 25 the horizontal pipe, a reciprocating stem working through this casing, a bell-crank connecting the inner end of the stem to the reciprocating rod, and means for operating the stem.

4. The combination, of a boiler, a blow-off 30 pipe consisting of a vertical part and a substantially-horizontal part connected thereto, the latter part being provided with a blow-off cock at a distance from the boiler, a reciprocating rod in each part of the pipe and provided 35 with radial pins, means for guiding the vertical rod, means for connecting it to the adjacent end of the horizontal rod, and means for reciprocating both rods, consisting of a device attached to the horizontal rod at a point be- 40 tween the blow-off cock and the vertical pipe.

In testimony whereof I hereunto affix my signature, in the presence of two witnesses, this 21st day of April, 1900.

CLARENCE R. PARTINGTON.
